INVENTOR

John W. Plenchner

ATTORNEY

UNITED STATES PATENT OFFICE.

JOHN W. PLENCNER, OF WARREN, MINNESOTA.

CLIP-PASSER.

1,297,007.

Specification of Letters Patent. Patented Mar. 11, 1919.

Application filed February 12, 1917. Serial No. 148,293.

To all whom it may concern:

Be it known that I, JOHN W. PLENCNER, a citizen of the United States, residing at Warren, in the county of Marshall and State 5 of Minnesota, have invented certain new and useful Improvements in Clip-Passers, of which the following is a specification.

This invention relates to a clip-passor and more particularly to a device adapted for 10 use by line-men in telegraph and telephone engineering for the purpose of expediting the erection of wires.

The primary object of the invention is to provide means for eliminating the necessity 15 of the line-men of ascending the poles for attaching the telegraph or telephone wires to the supporting wire or cable commonly designated as the "messenger".

Another object of the invention is to provide 20 an angularly disposed passer associated with the supporting cable or "messenger" and adapted to permit the supporting clips which retain the telephone or telegraph wire, to freely pass from the ground to their 25 proper positions on the "messenger".

A further object of the invention is to provide 30 a clip passer of this character which will guide the clips from a point on the ground to an elevated position whereby the clips 35 will be guided to properly catch upon the "messenger" for supporting the telephone and telegraph wire in its proper suspended position from the "messenger".

A further object of this invention is the 40 provision of clip-passor which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, wherein is illustrated 45 the preferred form of my invention, in which;

Figure 1 is a front elevation of a fragmentary portion of a telegraph pole showing the device associated therewith.

50 Fig. 2 is a top plan view thereof.

Fig. 3 is a section on the line 3—3 of Fig. 1.

Fig. 4 is a section on the line 4—4 of Fig. 1.

55 Fig. 5 is a perspective view of a detail of the invention.

Referring to the drawing, wherein is illustrated the preferred form of my invention, and in which like numerals of reference indicate corresponding parts throughout the 60 several views, the supporting pole A is provided, adjacent its top, with a retaining hook 1 which receives and supports the supporting cable 2 commonly designated as the "messenger". A guide bracket 3 is constructed from a suitable length of metal or other suitable material, and consists of the elongated arm 4 having a flange 5 integrally formed therewith and the flange is provided with suitable openings for receiving the fastening elements 6 whereby the flange may be rigidly fastened to the pole. As shown by Fig. 4 of the drawing, the arm 4 is spaced away from the flange for permitting the upper edge of the arm 4 to provide a 70 trackway 7 that will be free from obstructions whereby the supporting clips 8 may freely pass over the entire length of the arm. 75

The arm 4 will be disposed at an angle and is rigidly held in this position by the flange 5 as clearly shown by Fig. 1 of the drawing. The lower end of the arm 4 is provided with a plurality of openings 9 and one end of a conveying cable 10 has the strands of which it is constituted, separated and the ends 85 thereof are passed through the openings 9 and twisted on the opposite side of the arm 4 as shown in Fig. 5 of the drawing for securing the conveying cable 10 to the end of the arm. It is to be noted that the trackway 90 which is formed by one edge of the arm 4 is longitudinally aligned with the top of the cable 10 this being accomplished by the means of the manner of fastening the end of the cable to the arm 4. This construction 95 provides an unobstructed trackway for the clips 8 so that they freely pass from the conveying cable 10 and on to the trackway on the arm 4.

The upper end of the arm 4 is curved and 100 has its end in engagement with the "messenger" 2. The arch of curved end of the arm 4 permits the same to be slightly elevated above the "messenger" 2 so that the clips 8 may be raised and properly guided whereby 105 they will freely pass from the curved portion of the arm to the cable or "messenger" 2. The central portion of the curved end of the arm is provided with a supporting standard 10' the lower end of which is provided with 110 a bifurcation 11 for receiving the "messenger" 2 as clearly shown by Fig. 3 of the

drawing. This provides an additional support for the clip-passor and prevents movement thereof while the clips are passing over the same.

5 The clips which support the telephone or telegraph wire 12 are of the usual construction and by referring to Fig. 4 of the drawing it will be observed that each is provided with a hook 13 at its upper end and this 10 hook fits over the curved edge of the trackway 7 so that the clip is permitted to freely pass over the trackway when the telephone or telegraph is pulled in the direction indicated by the arrow in Fig. 1. The lower end 15 of each clip is also formed with a hook 14 for receiving the telephone or telegraph wire 12 in the usual manner.

In operation it is merely necessary to mount the clip-passor as shown by Fig. 1 of the drawing by attaching the flange 5 to the 20 telegraph pole and permitting the curved end to rest upon the "messenger" 2. The free terminal of the conveyer cable 10 is disposed adjacent the ground and fixed in any 25 suitable manner. The clip-passor and the conveyer cable 10 are then supplied with a plurality of clips having the telephone or telegraph wire attached in the usual manner so that all of the parts will be assembled as 30 shown in Fig. 1 and the device will then be ready for operation. It is merely necessary for the line-men to grasp the end of the telephone or telegraph wire and pull the same in the direction indicated by the arrow in 35 Fig. 1 and the wire will then be drawn from the source of supply on the ground while the clips will be fed to the telephone wire and the conveyer cable 10 to be drawn along the clip-passor and supplied to the "messenger" 40 2 in their proper relative positions. It is pointed out that the hooks 14 of the clips 8 have their bills turned slightly inwardly so that the telephone or telegraph wire is snugly held to the clip thereby preventing 45 the wire from slipping through the clip and also assisting the clip in its travel along the clip-passor. This operation may proceed until any desired length of wire has been supplied to the "messenger" 2 and the flange 5 50 may then be disconnected from the pole and removed.

From the foregoing it will be observed that a very simple and durable clip-passor has been provided, the details of which embody the preferred form. I desire it to be understood however, that slight changes in the minor details of construction may be made without departing from the spirit of the invention or the scope of the claims hereunto appended.

I claim:

1. A clip-passor comprising a guide bracket formed from an elongated arm having a portion of its length disposed at an

angle, means attached to the angularly disposed portion for supporting the arm, a curved portion formed at the upper end of the said arm, and a standard formed on and depending from the said curved portion for elevating the same and holding the same in 70 elevated position.

2. A clip-passor comprising a guide bracket formed from an elongated arm having a portion of its length disposed at an angle, means attached to the angularly disposed portion for supporting the arm, a curved portion formed at the upper end of the said arm, a standard formed on and depending from the said curved portion for elevating the same and holding the same in 80 elevated position, the edge of the said arm being rounded to provide a longitudinal trackway extending over the curved portion.

3. A clip-passor comprising a guide bracket formed from an elongated arm having a portion of its length disposed at an angle, means attached to the angularly disposed portion for supporting the arm, a curved portion formed at the upper end of the said arm, a standard formed on and depending from the said curved portion for elevating the same and holding the same in 90 elevated position, the edge of the said arm being rounded to provide a longitudinal trackway extending over the curved portion, 95 the lower end of the arm having a plurality of openings formed therein and adapted to receive the strands of the said conveying cable when the strands are separated and passed through the openings.

4. A clip-passor comprising a guide bracket formed from an elongated arm having a portion of its length disposed at an angle, means attached to the angularly disposed portion for supporting the arm, a curved portion formed at the upper end of the said arm, a standard formed on and depending from the said curved portion for elevating the same and holding the same in 105 elevated position, the edge of the said arm being rounded to provide a longitudinal trackway extending over the curved portion, 110 the lower end of the arm having a plurality of openings formed therein and adapted to receive the strands of the said conveying cable when the strands are separated and passed through the openings, the said frayed end of the cable permitting the said trackway and the upper edge of the said cable to be in longitudinal alinement.

5. A clip-passor comprising a guide bracket formed of an elongated arm having a straight portion provided intermediate its ends and adapted to be fixedly mounted, the intermediate portion of the arm being curved 125 and having one end of arcuate formation, and its opposite end provided with a plurality of apertures, a cable having its ends sepa-

rated and received in the said apertures to fix the cables to the end of the straight portion of the arm, and a plurality of clips having hooked portions adapted to engage over 5 the top edge of the said arm and depend below the same.

Copies of this patent may be obtained for five cents each, by addressing the "Commissioner of Patents, Washington, D. C."

In testimony whereof I affix my signature in presence of two witnesses.

JOHN W. PLENCNER.
